UNITED STATES PATENT OFFICE.

ELIE FRAGGI, OF NEW YORK, N. Y.

WINDOW SASH.

Application filed December 1, 1927. Serial No. 236,991.

The invention relates to window sashes, and improved means for adjusting the same, having means for revolving the window panels or sashes into different positions, whereby both sides of the glass may be conveniently cleaned from the inside of the building without danger to the operator, and whereby the sashes may be raised and lowered at will without interfering with each other, nor with the window shades, draperies, and curtains; affording perfect ventilation of an apartment or room in a building; and the object thereof is to provide improved construction and means whereby the above functions or results may be obtained. With these and other objects in view, the invention consists in the construction, combination, and arrangement of parts hereinafter described and claimed.

20 The invention is fully disclosed in the following specification, of which the accompanying drawing forms a part, in which the separate parts of my improvement are designated by suitable reference characters in each of the views, and in which:

Fig. 1 is an inside view of a window provided with my improvement or improvements;

Fig. 2 is a section on the line 2—2 of Fig. 1;

Fig. 3 is a section on the line 3—3 of Fig. 1, and on an enlarged scale;

Fig. 4 is a section on the line 4—4 of Fig. 1, and on an enlarged scale.

35 In the drawing forming part of this specification I have shown in Fig. 1, a window frame α composed of vertical side members α^2 and top and bottom transverse members α^3 and α^4 , all of which parts may be of the usual or any preferred construction, and mounted in said frame are the bottom sash b and top sash c , and both are composed of outer frame members b^2 and c^2 respectively, and inner revolving frame members b^3 and c^3 respectively.

45 The bottom sash b is shown partly raised in order to show more clearly the invention. As it has been stated above, it consists of a main outer sash frame b^2 and an inner sash frame member b^3 , and this comprises an inner part b^6 and an outer part b^7 between which the transparent panel b^4 is mounted, and these parts are connected at intervals with the screws e . The inner sash frame member b^3 is pivoted centrally of its sides as shown at b^8 to the outer sash frame mem-

ber b^2 , this pivotal connection consisting of a pin or bolt d passed outwardly through the sash members b^3 and b^2 and provided at its outer end with a nut d^2 countersunk in the sash frame member b^2 and at its inner end with a head d^3 , as shown in Fig. 4.

With this construction the inner sash frame member b^3 is free to revolve on its pivotal supports at b^5 , as it will be readily understood, and as it is shown in Fig. 2, where the bottom sash b^3 is shown partly revolved. The said inner sash frame member b^3 may be locked to the outer sash frame member b^2 when in its closed position by means of a suitable locking or securing device f shown in Fig. 3, and consisting of a pin pushed upwardly with a key, from the outer frame member b^2 to the inner sash frame member b^3 .

55 The outer sash frame members b^2 and c^2 comprise as shown in details in Figs. 3 and 4, a reenforcing light strip of metal g with a rubber cushion h on which the inner sash frame members b^3 and c^3 respectively adjust 80 themselves freely, smoothly, and tightly, and the cold air from the exterior can not enter the room when the window is closed. In Fig. 4, it will be noted that the edges or faces of the outer side members B and inner members $B3$ are straight whereas the top and bottom transverse or horizontal portions of the sashes provide a slightly concave-convex face or edge so that an air tight joint is produced.

90 The upper sash c is also composed of a main outer sash member c^2 and an inner sash member c^3 pivoted centrally of its sides to the main outer sash member c^2 at c^4 , and this pivotal connection, or the construction 95 thereof, is the same as that employed in connection with the bottom sash and shown in details in Figs. 3 and 4, and the inner sash member c^3 of the top window sash may be locked to, or secured to the main outer sash, 100 member c^2 by a locking device f similar in all respects to that employed at the bottom of the bottom sash.

105 It will be understood that the bottom and top sashes may be mounted in the usual or any desired manner, and may be counterbalanced and moved up and down in the usual way, and my invention is not limited to the use of any particular material in the construction or mounting of the sashes.

110 With my improvement the supplemental sash members b^3 and c^3 which carry the

transparent panels may be freely swung both forwardly and backwardly, inwardly and outwardly into any desired position, and the thorough cleaning of the transparent panels by an operator in the room or compartment is thus facilitated without danger to said operator.

I am aware that many types of revolving window sashes exist prior to my invention.

10 Aside from their complicated and elaborated metallic devices showing that they are specially destined for windows of metallic construction, said sashes have the disadvantage of interfering with the shades and curtains when the sashes are opened or rather revolved on their pivots for the purpose of aerating the room, such sashes pivoting directly on the casements or other fixed parts of the windows. Therefore those sashes are 20 not practical and suitable for dwelling houses and consequently people prefer the use of sash windows having their sashes raised and lowered with the aid of cords and pulleys. But in their turn those sashes while they 25 do not interfere with the shades and curtains, have the dangerous disadvantage that the outside of their panels can not be conveniently cleaned from the inside of the building without danger to the operator and 30 people are obliged to sit or stand on the outside narrow sills of the windows, in order to clean the outside of the window panels, and many accidents occur.

While the window shown with my drawing and my present specification has its sashes both revolving and at the same time moving up and down, and thus attains the advantage desired.

Having fully described my invention, what 40 I claim as new and desire to secure by Letters Patent, is:—

1. In a window, the combination with a frame, sliding sashes for said frame, each of said sashes comprising an outside frame member having an interior groove along its sides, top and bottom, a reenforcing strip and a cushion positioned in said groove, an inside sash frame in engagement with said reenforcing strip and cushion, pivots connecting said outside frame member and said inside sash frame, said pivots passing through the reenforcing strip and cushion and means for locking said inside sash frame to the outside member.

2. In a window, the combination with a frame, sliding sashes for said frame, each of said sashes comprising an outside frame member having an interior groove along its sides, top and bottom, a reenforcing strip

and a cushion substantially semi-circular in cross section positioned in said groove, an inside sash frame in engagement with said reenforcing strip and cushion, pivots connecting said outside frame member and said inside sash frame, said pivots passing through the reenforcing strip and cushion and means for locking said inside sash frame to the outside member.

3. In a window, the combination with a frame, sliding sashes for said frame, each of said sashes comprising an outside frame member having an interior groove along its sides, top and bottom, a flat reenforcing strip forming a seat and a resilient cushion held by said strip within said groove, an inside sash frame in engagement with said reenforcing strip and cushion, pivots connecting said outside frame member and said inside sash frame, said pivots passing through the reenforcing strip and cushion and means for locking said inside sash frame to the outside member.

4. In a window, the combination with a frame, sliding sashes for said frame, each of said sashes comprising an outside frame member having an interior groove along its sides, top and bottom, a flat reenforcing strip forming a seat and a resilient cushion held by said strip within said groove an inside sash frame in engagement with said reenforcing strip and cushion, horizontal bolts connecting said outside frame member and said inside sash frame, said pivots passing through the reenforcing strip and cushion and means for locking said inside sash frame to the outside member.

5. In a window, the combination with a frame, sliding sashes for said frame, each of said sashes comprising an outside frame member having straight sides edges and top and bottom concave edges and formed with a groove along its sides, top and bottom edges, a reenforcing strip and a cushion positioned in said groove, an inside sash frame having straight side edges and a convex top and bottom edge adapted to engage the concave top and bottom edges of the outside frame member, horizontal pivots connecting said outside frame member and said inside sash frame, said pivots passing through the said strip and said cushion and means for locking said inside sash frame to the outside member.

In testimony that I claim the foregoing as my invention, I have signed my name this 115 25th day of November, 1927.

ELIE FRAGGI.
